SAFETY RAZOR AND BLADE COMBINATION

William G. Adams, Greensboro, N. C.

Application September 30, 1931, Serial No. 566,123

13 Claims. (Cl. 30—75)

The invention relates to safety razors, particularly those of that type in which use is made of a flexible blade clamped between a body and a cap and has for its general and primary object 5 the provision of a novel razor and blade combination in which the construction, coaction and relation of the two is such that neither can be used without the other.

Heretofore in safety razors of the type where- 10 in a thin flexible blade is clamped between two principal members such as a cap or cover member and a body equipped with guards, and wherein the cap and body are positioned with respect to each other by means independent of 15 the shape of the blade, that is without utilization of the blade as means for positioning the main members with respect to each other, positioning and stabilization of the blade with respect to the cap and the body has generally 20 been accomplished by means of suitably placed lugs or studs projecting from one principal member into the other these studs frequently serving also as the positioning means for the principal members with respect to each other, 25 with coacting edges of the metal located either in the perimeter of, or in holes through the blade and lying between the planes conforming with its top and bottom surfaces.

In case a manufacturer, in the interests of 30 economy, or for any other reason, might wish to omit such lugs or studs, or in case he wishes a novel means of positioning a blade in his particular make of razor such as will preclude the use therein of any blade not specifically manufactured therefor, in which latter case the studs might be so shaped as to prevent their use as 35 blade positioning means except for preliminary purposes as the two blade clamping members of the razor approach each other, for instance 40 as contemplated in my co-pending application Serial No. 529,815, filed April 13th, 1931, utilization might be made of simply formed apertures in the main members of the razor coacting with 45 projections on the surface of the blade, and in the above referred to application I have provided 50 means of positioning the blade by utilization of the ends, or of the faces, of outstanding lugs flanged from the metal of the blade coacting with spaced portions of walls of suitably placed apertures in the cap and body of the razor.

In cases where long projections extending 55 from the surfaces, some of them the full length of the blade, coacting with longitudinal recesses in the cap and body have been proposed as joint- ly effecting blade positioning, and also cap and

body positioning, it is necessary that the full length of the projecting metal or of the surfaces of the slots in the cap and body with which the projections coact, or of both, be accurately formed, and the blades of such type as well as 5 those I have described above with lugs extending from the surfaces are open to certain objections, notably that of presenting difficulty in packing for purposes of marketing and of providing obstructions to fitting of the blades in 10 clamping means used by existing sharpening devices.

With a view to overcoming these objections and of providing means for positioning the blade in razors such as will prevent utilization in a 15 razor of particular make of any blade not provided with this particular blade positioning means, and providing razors and blades that can be cheaply constructed and for other reasons I have devised the novel combination constituting 20 the basis of the present application.

A very important object of the invention is to provide a razor and blade combination in which the blade is formed with means normally lying in its plane or coextensive therewith but adapted to be deflected or pressed out by means on one blade engaging member so as to be received and to fit within recesses in the other blade engaging member for the purpose of positioning the blade accurately with respect to the guards com- 30 monly provided so that the proper action of the blade will be assured.

Another object of the invention is to provide a razor and blade combination in which the parts are so constructed as to effect a preliminary positioning of the blade between the relatively movable body and cap prior to the actuation of means for moving the cap and body relatively to bring about clamping engagement 35 thereof with the blade, other positioning means integral with the blade subsequently coming into play for effecting the final accurate positioning of the blade between the body and cap.

A further object is to provide a razor and blade 45 combination in which means may be provided for maintaining the blade upon the body and preventing it from adhering to the cap, as it might otherwise when wet, when the cap is moved into released position with respect to the 50 body.

A more specific object of the invention is to provide a razor and blade combination in which the means coacting with positioning means on the blade may be carried either by the body or the 55

cap of the razor, there being no limitation in this respect.

Another object is to provide a blade having novel positioning means thereon adapted to cooperate with means on a holder.

A specific object is to provide a blade formed with novel positioning means of a flexible nature and which may, before tempering of the blade, be caused to project slightly beyond opposite sides of the opposite ends so as to prevent the blade from lying flat upon a supporting surface, this means not interfering, however, with flat packaging of the blades.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a fragmentary cross sectional view through a razor and blade combination constructed in accordance with one form of my invention,

Figure 2 is a longitudinal section,

Figure 3 is a section taken on the line 3—3 of Figure 2 showing the blade in plan,

Figure 4 is a cross section taken on the line 4—4 of Figure 3,

Figure 5 is a view similar to Figure 4 illustrating a slight modification,

Figure 6 is a longitudinal section showing a modified form of positioning means,

Figure 7 is a horizontal section taken on the line 7—7 of Figure 6,

Figure 8 is a detail cross section taken on the line 8—8 of Figure 6 looking in the direction of the arrows,

Figure 9 is a section taken on the line 9—9 of Figure 6 and looking in the direction of the arrows,

Figure 10 is a fragmentary plan view of the razor body and blade thereon and disclosing another variation,

Figure 11 is a cross section on the line 11—11 of Figure 10.

Referring more particularly to the drawing and especially Figures 1 to 4, I have shown a razor comprising a body 15 having guards 16 at its longitudinal edges and a convex seat for a blade 17 of the thin, flexible and usually double edged type. Coacting with the blade is a cap 18 having a screw connection with a handle 19 swivelly connected with the body. While it is immaterial which screw member is carried by the body and which is carried by the cap I have in the present instance illustrated the cap as carrying the male screw 20 received within a threaded socket 21 in the handle. These elements are conceivably reversible.

The blade 17 is formed with two oppositely extending tongues 22 normally lying in the same plane as the blade and capable of being flexed to project beyond one face thereof so as to be received within recesses 23 in the convex face of the body, these recesses being preferably of elongated rectangular shape with their outer ends defining shoulders 24 and with their inner portions curved and merging gradually into the convex face or blade seat. The ends of the blade 70 are preferably formed with extensions 25 which project beyond the body and the cap to facilitate handling.

In addition to the male screw 20 the cap carries studs preferably integral therewith having frusto-conical or tapered base portions 26 and

cylindrical end portions 27, the latter being adapted to fit within circular holes 28 in the tongues 22 and to be received within holes 29 in the body communicating with the recesses 23. At its center the blade is formed with a circular hole 30 of sufficient diameter to pass the male screw 20. The threaded stud or screw 20 is not of uniform diameter throughout but preferably has a constricted neck portion 31 adjacent its juncture with the cap so that in itself it cannot serve to position the blade.

In the use of this form of the combination, the blade may be initially laid upon the convex seat afforded by the body 15 with the holes 28 in the tongues registering substantially with the holes 27 in the body and with the central hole 30 registering substantially with the threaded socket 21. Instead of this, the cap 18 may be inverted and the blade 17 laid upon it with the holes 28 engaging upon the ends 27 of the studs carried by the cap and with the hole 30 at the center of the blade engaging upon the threaded stud or screw 20. Regardless of which method is resorted to, it is clear that there will be an initial positioning of the blade with respect to either the body or the cap. The cap and body members are then moved relatively to start the threaded stud or screw 20 into the socket 21, whereupon the handle 19 is rotated with respect to the body and cap for drawing the cap toward the body into clamping relation to the blade. As this is done the frusto-conical or tapered base portions of the studs on the cap engage against the edges of the openings 28 in the tongues and flex the tongues out of the plane of the blade so that they will enter the recesses 23 provided for their accommodation. If the blade be initially laid upon the body without the holes 28 registering exactly properly with the holes 27 it is clear that the tapering of the bases 26 will act to shift the blade to a certain extent for bringing about proper registration so that the blade will be positively and accurately positioned with respect to both the body and the cap.

As a slight modification, I may resort to the construction shown in Figure 5 which discloses the same arrangement as Figures 1 to 4 except that the terminal portions of the studs 32 carried by the cap 33, corresponding to the cap 18, are formed with peripheral grooves 34 so as to make it still more impossible to use a blade not specifically designed for use with the razor though these studs will provide preliminary positioning means.

In Figures 6 to 9 inclusive I have illustrated a modification of the invention in which the positioning studs are carried by the body instead of by the cap. Referring to these figures in detail, the numeral 35 designates the body having a convex blade seat and guards 36 at its longitudinal edges. Swivelled at the center of this body is a handle 37 formed with a threaded socket 38 to receive a threaded stud or screw 39 carried by the cap, this screw having a reduced neck 40 at its juncture with the cap. Moreover the body is formed with recesses 41 somewhat similar to the recesses 23 in the first described form and having their outer ends defining shoulders 42 corresponding to the shoulders 24 and having their inner ends inclined or curved and merging into the convex blade seat. However, in this instance the recesses 41 differ from the recesses 23 in the particular that at their outer ends they communicate with grooves 43 having flaring or

inclined surfaces 44 leading thereto for a purpose to be described.

In this form of the invention the body is provided with a pair of upstanding studs 45 rising from the recesses 41 and having reduced or constricted neck portions 46, these studs being adapted to be received within recesses 47 in the underside of the cap.

The blade 48 used in this modification is somewhat similar to the blade 17 and is likewise preferably provided at its ends with extension 49 projecting beyond the ends of the body and cap for facilitating manipulation. The blade is formed centrally with a hole 50 through which the threaded stud 39 is adapted to pass, and is also formed with a pair of tongues 51 having circular holes 52 therein of a size corresponding to the heads of the studs 45 but appreciably larger than the reduced necks thereof so that reliance 15 cannot be placed upon these studs and upon the threaded stud 39 for anything more than mere preliminary positioning of the blade. The recesses 41 above mentioned are designed to receive the tongues 51 when they are deflected 20 from the plane of the blade and to effect such deflection and accomplish proper positioning of the blade I provide relatively small projections 53 on the underside of the cap engageable with the outer end portions of the tongues 51 for 25 forcing them into the recesses 41 so that reduced extensions or tits 54 on the ends of the tongues will be caused to enter and fit snugly within the grooves 43 as illustrated in Figure 9.

In the use of this form of the invention the blade is initially laid upon the convex seat or face on the body, the stud 45 passing through the holes 52 in the tongues 51 and serving as preliminary positioning means. Care should, however, be taken not to move the blade in any direction after it rests upon the seat as the reduced necks 46 of the studs 45 and the reduced neck 40 of the threaded stud 39 are of considerably less diameter than the holes 52 and 50, respectively, and will therefore permit the blade 45 to be shifted out of the initially proper position. The cap is then applied and the studs 39 started into the socket 38, the handle 37 being rotated to draw the cap into clamping relation to the blade. When this is done the projections 53 will engage against the tongues 51 and deflect them out of the plane of the blade so that they will occupy a position within the recesses 41. As this deflection or outward swinging of the tongues takes place the reduced extensions 54 on the ends thereof will enter the grooves 43 and will consequently operate positively to prevent shifting movement of the blade in any direction whatsoever. If the preliminary position of the blade be done carelessly or if the blade be shifted 50 slightly from its proper initial position it should be apparent that when the cap is clamped down the inclined surfaces 44 leading to the grooves 43 will act to guide the extensions 54 into the grooves so that proper positioning will be assured.

In all forms of the invention disclosed it will be apparent that the positive positioning of the blade with respect to the body and cap and the positioning of the cap and body with respect to each other will maintain the blade with its edges in the exactly proper relation to the guards at the longitudinal edges of the body so that no portion of the edge may project to a greater or less extent than is proper. The razor is of course used in the ordinary manner. When its use is no longer desired the handle 19 or 37 is unscrewed

so that the cap may be removed so that the blade may be taken out for cleaning and drying. The other razor parts should of course also be cleansed.

When the razor is wet, for instance as the result of holding it under a stream issuing from a faucet there is a natural tendency for the blade to adhere to the cap when the cap is released and removed. To prevent this I may resort to the expedient shown in Figures 10 and 11 where- 5 in the construction is identically the same as in Figures 6 to 9 except for the location of the tongue engaging projections 55 carried by the cap, these projections in this instance engaging against the tongues 51 at the sides of the openings 52 therein instead of beyond the openings as in Figures 6 to 9, and the replacement of the studs 45 by somewhat hook-like elements 56 which perform the same preliminary positioning function but which on account of their lateral 10 15 20 25 inclination will coat with the edges of the openings 52 in the tongues for preventing them from riding off and consequently preventing the blade from adhering to the cap.

A feature of importance is that by flexing the 25 tongues 22 or 51, before the blade is tempered, so that their ends will be deflected slightly from opposite sides of the blade, they will prevent the blade from lying flat upon a supporting surface.

Naturally this will enable the blade to be picked 30 35 up more readily. The tongue, if permanently deflected from the body of the blade without an abrupt angle, that is with little or practically no bending of its metal in the portion joining the body of the blade, and which portion is of com- 40 paratively narrow width, as shown, is obviously flexible and is accordingly adapted to provide resilient or yielding contact at its end with the bottom of the orifice in the razor member, or with a table top or other surface on which it 45 may rest. This resilient characteristic of the tongue, unhampered by any restraint at its free end, whether the tongue is permanently deflected from the plane of the blade or is deflected therefrom by the means provided on one of the 50 members during clamping action on the blade, which means contacts the tongue inwardly of its end, is especially effective in providing dependable contact with the co-acting blade position- 55 ing parts of the members of the razor. Con- 55 stant contact of the end of the tongue with the latter is assured irrespective of varying distance between the clamping members when accom- 60 plishing varying flexure of the blade and irre- 65 spective of any varying depth of recesses due to manufacturing variations. By so locating the tongue that its free end is near the end of the blade, the positioning means carried by said free end provides effective means against minute ro- 65 tation of the blade in the razor. Furthermore this resiliency, in case of the tongue being per- 70 manently deflected from the plane of the blade, is of especial advantage in that it readily permits of the entire tongue's being pressed back into the plane of the blade to obviate interference with sharpening devices and to facilitate pack- 75 ing, and it also prevents danger of breakage when mashed. Moreover as the tongue has a relatively narrow neck portion at its juncture with the blade and as this portion is adapted to assume a warped shape at the location between the flexed body of the blade and the curved remaining portion of the tongue, which curvatures are formed by generatrices at right an-

gles to each other the deflection of the tongue from the plane of the blade produces little or no stiffening effect interfering with flexing of the blade.

5 In all forms of the invention it will be observed that I have made adequate provision for preliminary positioning of the blade and also for positive securing of the blade in final accurately positioned relation with respect to the body and cap. Obviously a blade of ordinary type such as one unprovided with the tongues could not be used as when the main parts are brought together into clamping relation to the blade the blade, being brittle, would become broken. An 10 other consideration is that all of the parts, that is to say the body, cap, studs, blade and details of the latter cooperate in every respect so that the holder or razor proper and the blade constitute what may be termed an inseparable entity 15 or combination, each being dependent on the other and incapable of satisfactory employment without its complement: In this way the use of a blade not specifically intended for my razor is entirely precluded and a manufacturer of the 20 combination may be in a position to monopolize the manufacture and sale of the appropriate blades, thereby avoiding possibility of his razor falling into disrepute as the result of the employment of improper and unauthorized 25 blades in association therewith.

From the foregoing description and a study of the drawing it is believed that the construction, operation and advantages will be readily apparent to one skilled in the art without further explanation.

While I have shown and described the preferred embodiments of the invention, it should be understood that the disclosure is merely an exemplification of the principles involved as 40 the right is reserved to make all such changes in the details of construction as will widen the field of utility and increase the adaptability of the device provided such changes constitute no departure from the spirit of the invention or 45 the scope of the claims hereunto appended.

Having thus described the invention, I claim:

1. A razor comprising the combination of main members with a blade interposed therebetween and adapted to be clamped thereby, one of said 50 members having a recess therein and the other having a projection, the blade having a struck out tongue permanently deflected from the normal plane thereof having a free end adapted to enter the recess, means on the tongue for positioning the blade with respect to one of said main members comprising an opening in the tongue having its edges adapted to coact with said projection.

2. A razor comprising the combination of main 60 members one of which is equipped with a handle, a blade adapted to be clamped between said main members and formed with a resilient tongue having a free end, said tongue also having an open portion, one of said members being recessed to 65 receive the tongue, means for preliminarily positioning the blade upon one of said members, and means cooperating with the edge of the open portion of the tongue for flexing the tongue to cause the same to enter the recess when said main 70 members are disposed in clamping relation to the blade.

3. A razor comprising the combination of a pair of main members one of which is equipped with a handle, and a blade interposed and adapted 75 to be clamped therebetween, one member being

formed with recesses, said blade being formed with tongues struck out therefrom normally lying in the plane thereof and adapted to be flexed into the recesses, and projections carried by the other main member and engageable through the 5 tongues for positioning the blade with respect to said main members, said projections including tapered base portions and reduced terminal portions and the tongues having holes permitting passage of the terminal portions and having their 10 edges engageable by the tapered base portions.

4. A razor comprising the combination of a pair of main members one of which is equipped with a handle, and a blade interposed therebetween and adapted to be clamped thereby, one 15 main member having recesses and projections located therewithin, the blade being formed within its boundaries with flexible tongues apertured to be engaged upon said projections to effect preliminary positioning of the blade with respect to 20 the main members, and means on the other main member engageable with said tongues for flexing the same into said recesses when the main members are in clamped relation to the blade for finally positioning the blade with respect to the 25 main members.

5. A razor comprising the combination of a pair of main members one of which is equipped with a handle, and a blade interposed therebetween and adapted to be clamped thereby, one main member having recesses and projections located therewithin, the blade being formed within its boundaries with flexible tongues apertured to be engaged upon said projections to effect preliminary positioning of the blade with respect to the main 30 members, and means on the other main member engageable with said tongues for flexing the same into said recesses when the main members are in clamped relation to the blade for finally positioning the blade with respect to the main 35 members, said projections having reduced neck portions of less size than the aperture in the tongues so as to render the preliminary positioning means ineffective when the main members are in clamping engagement with the blade.

6. A razor comprising the combination of a pair of main members one of which is equipped with a handle and a blade interposed between them and adapted to be clamped thereby, one main member being formed with recesses and the blade 50 being formed within its confines with flexible tongues adapted to be flexed into the recesses, means for preliminarily positioning the blade upon said main member, and projecting means carried by the other main member and engageable with the tongues for forcing them into the recesses for effecting final positioning of the blade with respect to the main members, said recesses having flaring sides for guiding the tongues thereinto.

7. A razor comprising the combination of a pair of main members one of which is equipped with a handle and a blade interposed between them and adapted to be clamped thereby, one main member being formed with recesses and the 65 blade being formed within its confines with flexible tongues adapted to be flexed into the recesses, means for preliminarily positioning the blade upon said main member, and projecting means carried by the other main member and engageable with the tongues for forcing them into the recesses for effecting final positioning of the blade with respect to the main members, said preliminary positioning means acting to maintain the blade upon the main member initially engaged 70

thereby and to prevent it from adhering to the other main member when the main members are moved apart.

8. A razor blade of the thin flexible type adapted to be clamped between relatively movable members, the blade being formed with struck out tongues adapted to be flexed out of the plane of the blade and adapted to cooperate with means on said members for effecting positioning, the 10 blade being centrally apertured and said tongues being apertured.

9. A razor blade of the thin flexible type adapted to be clamped between relatively movable coacting members, the blade being formed with 15 struck out tongues extending in opposite directions from the center and initially deflected slightly from the plane of the blade at opposite sides thereof for preventing the blade from lying flat upon a support, said tongues having open 20 portions defining interior edges adapted to cooperate with means on said members for effecting positioning of the blade with respect to the members.

10. A razor blade of the thin flexible type adapted to be clamped between relatively movable members, the blade having a struck-out 25 flexible tongue with a free end, the free end of the tongue having an open portion providing edges adapted to cooperate with means on the relatively movable members for effecting positioning of the blade with respect to the members.

11. A razor blade of the thin flexible type adapted to be clamped between relatively movable members, the blade having a struck-out 30 flexible tongue with a free end, the free end of

the tongue having an open portion providing edges adapted to cooperate with means on the relatively movable members for effecting positioning of the blade with respect to the members, said tongue normally lying in the plane of the 5 blade and being but temporarily deflected therefrom upon clamping engagement of the blade by said movable members and returning to said normal position upon release of the clamping engagement.

12. A razor blade of the thin flexible type adapted to be clamped between relatively movable members, the blade having a struck-out flexible tongue with a free end, the free end of the tongue having an open portion providing 15 edges adapted to cooperate with means on the relatively movable members for effecting positioning of the blade with respect to the members, said tongue being normally deflected from the plane of the blade and capable of temporary disposition in the plane thereof under the influence 20 of pressure and returning to normal position upon the release of clamping pressure.

13. A razor blade of the thin flexible type adapted to be clamped between relatively movable members, the blade having a struck-out flexible tongue with a free end, the free end of the tongue having a reduced outward extension 25 and the tongue being adapted to be temporarily 30 flexed so that said reduced extension will be received within a recess in a coacting member for effecting positioning of the blade upon the application of clamping pressure.

WILLIAM G. ADAMS. 35
